UNITED STATES PATENT OFFICE.

HENRY H. LANG, OF BUFFALO, ASSIGNOR TO WALTER M. BROWN, OF ALBANY, NEW YORK.

SECTIONAL LADDER.

SPECIFICATION forming part of Letters Patent No. 518,961, dated May 1, 1894.

Application filed June 19, 1893. Serial No. 478,152. (No model.)

To all whom it may concern:

Be it known that I, HENRY H. LANG, a citizen of the United States of America, residing at Buffalo, Erie county, New York, have invented certain new and useful Improvements in Sectional Ladders; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

The object of my invention is to provide a new and improved sectional ladder.

In the drawings Figure 1, shows a side elevation of one of my rungs; Fig. 2, a similar view of a rung with a portion of its side broken away showing it to be a tube; Fig. 3, a front elevation of two sections of my ladder set together in operative construction, and Fig. 4, a side elevation of one of the side bars.

The sections 1 and 2 are arranged so that the upper end of the lower section and the lower end of the upper will lie together as shown in Fig. 3, the U shaped opening 6 in the lower ends of the side bars of the upper section setting astride of the prolonged rung 3 while the U shaped openings in the upper ends of the side bars of the lower section wholly or partly embrace the lower rung in the upper section forming a union of the two sections that prevents all flexion of the jointure so made. The ends of the prolonged rung 3 protrude beyond the outer faces of the side bars of the upper section sufficiently to allow of the ends of the rung, which are threaded, to carry a threaded nut 5 and leave room for enough back slack to the nut to allow of setting the sections together easily, and then tightening the nut and firmly holding the sections together, the nut being turned by means of the wings 7. The ends of the prolonged rung 3, which is preferably a tube or piece of common gas pipe, forming a refractory rung, is preferably upset after the nut 5 is in place, so as to prevent the nut 5 from being backed off the end of the rung, the upset being shown at 8; and the threads on the rung at 4. I prefer the upset 8 in preference to any other

form of offset as it is easily made by simply turning over the whole or a part of the end of the rung. The rung 3 is held fast in the side bars 1 preferably by means of pins 9 driven through the side bars and the holes 10 55 in the rung.

Heretofore sectional ladders have been made having a prolonged rung made in parts or sections by setting sockets or thimbles on the end of the said rung and setting a headed bolt in said socket or thimble, the outer or threaded end of the bolt forming the extreme end of the rung and such rungs I denominate compound rungs as they are formed of pieces or in sections while my rung I denominate a 65 unit rung, as it is in one unbroken whole and I have so termed it in the claims to distinguish it from such compound rungs. With all compound rungs, the difficulty has been that the parts work loose and soon become troublesome, and where one part is made of wood and the rest of metal, the shrinking of the wood is partly the cause of this difficulty, which difficulty I have overcome by employing a unit rung as shown. Ladders of this 70 general description have also been made in which the overlapping ends of the united sections have been locked together by means of collars and pins, the pins being attached to the device by means of a chain to prevent 75 loss, the said pin when in place preventing the sections from separating but, such pins would rust and become bent and would not operate readily and I have overcome this difficulty by threading the ends of my rung and 80 using a threaded nut which is kept from loss by the upset on the end of the rung thus providing a cheaper and more serviceable locking device. The operation of my device is as follows: The sections being set together as 85 shown in Fig. 3, the nut 5 is turned tightly against the outer surface of section 2 which pinches or crowds the sections together and holds them in place and when it is desired to remove them the nut 5 is slackened back until 90 the sections can be taken apart but, in slackening back on the nut the upset 8 prevents the nut from disengaging with the end of the rung 3 and it can never be lost. To prevent 95 rust from stopping the action of the nut, the 100

threads are made coarse and work loose and a little oil will readily cause the nut to turn.

What I claim is—

1. In a sectional ladder, a unit rung projecting beyond the outer faces of the side bars when in extension, the outer ends thereof being threaded and carrying a threaded nut and arranged to allow of back slack to said nut when the sections are in extension, the ends of the rung being provided with a projection arranged to prevent the nut from being backed off the rung substantially as described.
2. In a sectional ladder, a refractory tubular unit rung projecting beyond the outer faces of the side bars when in extension, the

outer ends of said rung being threaded and carrying a threaded nut meshing with the threads on the rung, said rung being arranged to allow of back slack to said nut when the sections of the ladders are in extension, the ends of the rung having an offset that the nut may not be backed off the rung substantially as described.

In testimony whereof I affix my signature in presence of two witnesses.

HENRY H. LANG.
